Term of patent 14 years

Int. Cl. D23—02

U.S. Cl. D23—71

Fig. 1.

FIGURE 1 is a perspective view of a water closet enclosure or similar article showing my new design.

FIGURE 2 is a cross-sectional view taken on line 2—2 of FIGURE 1.

FIGURE 3 is a cross-sectional view taken on line 3—3 of FIGURE 1.

FIGURE 4 is a perspective view of a modified form of the water closet enclosure shown in FIGURE 1.

FIGURE 5 is a front elevational view of FIGURE 4.

FIGURE 6 is a side elevational view of FIGURE 4.

The dominant features of my design reside in the portions shown in full lines, the fragmentary broken line representation of a portion of a bathroom in FIG. 1 is for purposes of illustration only.

I claim:

The ornamental design for a water closet enclosure or similar article, as shown and described.
